CLAIM

The ornamental design for a closure, as shown and described.

DESCRIPTION

FIG. 1 is a front perspective view of the closure of the present invention.

FIG. 2 is a front elevational view of the closure in FIG. 1.

FIG. 3 is a top plan view of the closure in FIGS. 1-2, the bottom of the closure forming no part of the claimed design.

FIG. 4 is a side elevational view of the closure in FIGS. 1-3, the opposing side elevational view being a mirror image of FIG. 4; and,

FIG. 5 is a rear elevational view of the closure in FIGS. 1-4.
